ARTIFICIAL LIMB

Joyce Otterman, Blyth, Northumberland,
EnglandApplication November 26, 1946, Serial No. 712,307
In Great Britain January 1, 1946

8 Claims. (Cl. 3—12)

1

This invention provides an artificial arm, for use in cases of amputation below the elbow, which comprises a rotary driving member at the wrist for imparting operating movement to a hand or other appliance, an operating member actuatable by a flexion cord, wire or the like to impart rotary movement to the driving member, and a selector mechanism, coupling the operating member to the driving member, and comprising a reversing gear for determining the direction in which the operating member will rotate the driving member.

The flexion cord, as is well known, is operated by shoulder movement, chest movement or pedal movement of the person fitted with the arm, and it is usual practice to operate the hand by a push rod arrangement from the flexion cord, which push rod causes a pivoted thumb to be pulled to open position in relation to fixed fingers against the action of a spring. The use of a rotary driving member in place of a push rod is of great practical convenience, since, as explained in my United States application No. 646,133, now Patent No. 2,477,463, it enables a hand of the construction described in E. W. Hobbs' United States application No. 644,498, now Patent No. 2,464,577, to be used in conjunction with the arm the subject of the present invention. Also, it is of particular value when a screw driver appliance is substituted for the hand. The reversing gear is of value, in that it enables repeated traction on the same flexion cord to be used for rotating the driving member alternately in opposite directions, e. g. to open and close the hand.

The wrist mechanism comprises a metal sleeve 15 formed at its end with an inturned flange 17 and having a slot 16 for the reception of the base plate 18 of an artificial hand 19 of the construction described in United States application No. 644,498. The hand includes a screw 20 for imparting opening and closing movement to the fingers when rotated by engagement between a driver 21 fixed to the screw and a driving member 22 in the wrist fitting. It will be appreciated, however, that the hand may be replaced by any other appliance, e. g. a screw driver, a split hook or the like, having a base plate such as 18, and a screw and driver, such as 20, 21 for imparting operating movement to the appliance.

As fully described in United States application No. 662,650, now Patent No. 2,427,974, the driving member 22 is mounted within a barrel 23 so as to be free to rotate in the barrel, and is held by a spring clip 24 against axial movement in relation to the barrel, and the driving member 22 is coupled to a driving shaft 25 of flattened section

2

by pins 26. Coupling of the hand to and uncoupling of the hand from the wrist fitting are controlled by a control lever 27, all as described in United States application No. 662,650.

5 The selector mechanism 12 operates, as will now be described, to determine whether successive tractions on a flexion cord 28 will rotate the shaft 25 in the same direction, or in opposite directions. Normally, and with the parts in the position shown, successive tractions on the flexion cord will rotate the shaft 25 in opposite directions to effect alternate opening and closing movements of the fingers. Sometimes, however, the wearer may desire to rotate the shaft 25 repeatedly in the same direction, as for example when a screwdriver appliance is fitted to the hand. This may be effected, by operation of a control lever 29 (Fig. 1), as later described.

20 Preferably the reversing gear is arranged to operate automatically after completion of each traction stroke on the flexion cord, so that repeated traction strokes will rotate the driving member in opposite directions, although manually operable means may be provided for rendering it ineffective should it be desired to turn the driving member a number of times in the same direction, by repeated pulls on the flexion cord, e. g. as when operating a screw driver appliance.

25 The hand or other appliance may be permanently secured to the wrist, but it is preferred to make it detachable, using for the purpose the connection described in my U. S. application No. 662,650.

30 One form of artificial arm according to the invention will now be described in detail, by way of example, with reference to the accompanying drawings, in which:

35 Fig. 1 is a section through the lower part of the arm, showing the selector mechanism in side elevation.

40 Fig. 2 is a corresponding top plan view of the selector mechanism.

45 Figs. 3—6 are sections taken respectively on the lines III—III, IV—IV, V—V and VI—VI in Fig. 1, and

50 Fig. 7 is a section on the line VII—VII in Fig. 2.

In all figures the parts are shown in home position, i. e. in the position they occupy prior to the exertion of traction of the flexion cord. Like reference numerals designate like parts throughout the figures.

55 The arm comprises a bucket 10 to fit the stump, a wrist fitting 11 of the construction described in United States application No. 662,650, and a se-

lector mechanism 12. The bucket is attached to a plate 13 by screws 14.

The flexion cord 28 is double-ended, and it passes under a pulley 30 (Figs. 2 and 7) and each of its ends is taken round, and attached to, one of a pair of pulleys 31, 131. Traction on the flexion cord will therefore rotate the pulleys in opposite directions, pulley 31 rotating anticlockwise and pulley 131 clockwise as seen in Fig. 5. The pulleys 31, 131 are respectively fixed to downwardly extending spindles 32, 132 (Fig. 3), around which are coiled torsion springs 33, 133 respectively. The lower ends 34, 134 of the springs are turned into holes in the spindles, while their upper ends bear against a boss 35 surrounding the shaft 25, the upper end 136 of spring 133 being shown in Fig. 1. The springs 33, 133 therefore return the pulleys 31, 131 to the home position illustrated, when the traction on the flexion cord is released.

Beneath the pulleys 31, 131, and rotatably mounted on spindles 32, 132 respectively, are a pair of gear wheels 37, 137 meshing (see Figs. 4 and 6) with a gear wheel 38 fixed to the shaft 25. The upper faces of gear wheels 31, 137 are formed with ratchet teeth 39, 139 respectively (Fig. 4). In a slot 40 in pulley 31 is a pawl 41, mounted on a pivot pin 43 and urged by a spring 42 into position to engage the ratchet teeth 39 and couple the pulley 31 to the gear wheel 37. A similar pawl 141 is provided in a slot 140 in pulley 131, the pawl being pivoted on a pin 143 and urged by a spring 142 into position to engage ratchet teeth 139 and couple the pulley 131 to the gear wheel 137.

In the home position of the pulleys, both pawls are held out of engagement with their ratchet teeth by engagement of their noses 44, 144 with a plate 45. As the pulleys are rotated away from home position, the noses of the pawls ride down cam faces 46 on the plate 45 (Fig. 6) and become free. One only of the pawls can, however, engage its associated ratchet teeth, when their noses are freed from the plate 45. This selective engagement of the pawls with the ratchet teeth is controlled by a ratchet wheel 47 (Figs. 2 and 4) loose on a pin 48. The ratchet wheel 47 has fourteen ratchet teeth, which teeth are engaged, as later described, by a pawl 49 to feed the ratchet wheel anti-clockwise as seen in Fig. 2 by one tooth on each return movement of the pulleys to home position. A check pawl 60 prevents the ratchet wheel 47 from being so fed by more than one tooth. On its undersurface, the ratchet wheel 47 has seven teeth 50, these teeth being separated by notches 51 (see Fig. 1). Pivoted on a common pivot pin 52 (Fig. 1) are a pair of levers 53, 153 formed with pads 54, 154 respectively, which are located above humps 55, 155 on the pawl 41, 141 as shown in Fig. 3. The levers 53, 153 carry inwardly extending wires 75, 175 which cooperate with the teeth 50 and notches 51 on the undersurface of the ratchet wheel 47.

In the position of the parts shown in Fig. 4, the wire 175 is opposite a tooth 50 and the wire 75 opposite a notch 51 in the ratchet wheel. When the pulleys move from home position, and the pawls are freed from the plate 45 as already described, the springs 42, 142 will tend to rock them into engagement with their respective sets of ratchet teeth. This rocking movement of the pawls will tend to lift the pads 54, 154 and therefore to lift the wires 75, 175. Wire 175 cannot however rise, because it is obstructed by the teeth 50. Pawl 141 is therefore prevented from

moving into engagement with the ratchet teeth 139, and gear wheel 137 remains uncoupled from pulley 131. Wire 75, being opposite a notch 51, is however free to rise, with the result that pawl 41 can move to coupling position to couple gear wheel 37 to pulley 31. The traction stroke of the cord, which rotates pulley 31 anti-clockwise as seen in Fig. 5, is therefore effective to rotate gear wheel 38 and shaft 25 clockwise as seen in Fig. 6.

When, however, ratchet wheel 47 is fed forward one tooth by the pawl 49 as the pulleys return to home position, a tooth 50 will come into position above wire 75 and a notch 51 above wire 175. On the next traction stroke therefore, pawl 141 will move to coupling position and pawl 41 will be prevented from so moving, with the result that gear wheel 38 and shaft 25 will be rotated in the reverse direction, i. e. anticlockwise as seen in Fig. 6.

The pawl 49 is pivotally mounted at 56 on a sliding carriage 57 and urged by a spring 58 into engagement with the ratchet wheel 47. A two limbed spring 59, supported by a screw 61, engages holes 62 (Fig. 5) in the carriage 57 and urges the carriage to the right as seen in Figs. 1, 2 and 5. Such movement is, however, prevented in the home position of the pulleys by engagement of pins 63, 163 carried by the pulleys with extensions 65, 165 of the carriage. When however the pulleys have travelled a short distance from home position the carriage 57 is free to travel to the right. On the return movement of the pulleys, the pins 63, 163 pick up their respective extensions and return the carriage to the left, thereby causing the pawl 49 to feed the ratchet wheel 47 anti-clockwise by one tooth to reverse the position of the pawls 41, 141 on the next traction stroke, as already described.

Normally therefore alternate traction strokes rotate the shaft 25, in opposite directions. When it is desired to effect successive movements of shaft 25 in the same direction of rotation, this may be done by incompletely relieving the pull on the flexion cord, so that the pulleys do not return sufficiently to feed the carriage 57 to the left. Reversal of the coupling may however be positively prevented by moving the lever 29, the free end of which projects from the bucket, anti-clockwise, as seen in Fig. 1, about its pivot 64. A cranked extension 66 of the lever 29 engages a slot 67 in a catch arm 68 pivoted on the pin 52. When the lever 29 is so moved, arm 68 is rocked anticlockwise as seen in Fig. 7 to bring a tooth 69 thereon into position behind an upward projection 70 on the carriage 57. Movement of the carriage 57 to the right by the spring 58, when the carriage 57 is freed from the pins 63, 163, causes the projection 70 to rock the catch arm 68 clockwise against a spring 168, the pawl thereafter returning to engage its tooth 69 behind (i.e. to the left of) projection 70, thus preventing the carriage 57 from being returned to the left when again engaged by the pins 63, 163. The carriage 57 being thus locked in its right hand position, the pawl 49 cannot operate on the return movement of pulleys 31, 131 towards home position to feed the ratchet 47 forwards. Reversal of the direction of rotation of the shaft 25 is therefore prevented until the lever 29 is returned to the illustrated position. Pawl 63 is then returned to the position shown, with the result that pulleys 31, 131 can complete their movement to home position, pins 63, 163 moving the carriage 57 to the left to reverse the coupling.

The purpose of plate 45, which it will be recalled disengages both pawls 41, 141 near the end of the return movement of the pulleys is as follows. Without it, if the hand were fitted to the wrist mechanism with the fingers closed, and the selector mechanism were conditioned for rotation of the shaft in the direction to close the fingers, the user would be unable to move the pulleys sufficiently from home position to effect reversal of the coupling and so would be unable to open the fingers. Due to the fact that plate 45 operates to hold both pawls disengaged during the early part of the movement of the pulleys away from home position the user can, even in the circumstances just mentioned, rotate the pulleys sufficiently away from home position to allow the carriage 37 to move to the right. Then, when the selected pawl engages and he is unable to pull the cord further due to the hand being fully closed, and the selected pawl tending to close it further, he is able to reverse the coupling by relieving the pull on the cord.

The selector mechanism is enclosed in a casing 72 of transparent plastic material. This casing is shown in Fig. 7 but omitted from the other figures.

While in the construction illustrated the selector mechanism is shown fitted directly to the wrist fitting it may, in cases where amputation is higher up, e. g. just below the elbow, be located further from the wrist fitting so as to give a better balance to the arm, the shaft 25 in this case of course being longer. Again, in case of amputation at the wrist, the selector mechanism and its associated operating pulleys can be built into the base of the hand.

What I claim as my invention and desire to secure by Letters Patent is:

1. An artificial arm, for use in cases of amputation below the elbow, and comprising a bucket to fit the stump, a wrist fitting attached to the bucket and adapted to be detachably coupled to an artificial hand, a rotary driving member within and extending axially of the wrist fitting for imparting rotary movement to the hand when coupled to the wrist fitting, an operating member within the arm which is geared to the driving member and is actuatable by a flexion cord to rotate said driving member, a reversing mechanism which is normally operative to cause successive pulls on the flexion cord to rotate said driving member in opposite directions, and manually operable means for disabling said reversing mechanism to permit successive pulls on the flexion cord to rotate said driving member in the same direction.

2. The combination, with a rotary driving member for imparting, according to its direction of rotation, opening and closing movement to the fingers of an artificial hand, of a pair of pulleys spring biased to a home position, said pulleys being rotatable in opposite directions away from said home position by traction on a flexion cord, a pair of gear wheels, one associated with each of said pulleys, a toothed wheel meshing with both of said gear wheels and arranged to impart rotary movement to said driving member, means for alternatively coupling the gear wheels to the pulleys so that but one gear wheel at a time can be coupled to its pulley and a pawl and ratchet gear which is rendered operative, as the pulleys near the home position, to reverse the couplings between the pulleys and the gear wheels.

3. An artificial arm, for use in cases of amputation below the elbow, and comprising a bucket

to fit the stump, a wrist fitting attached to the bucket and adapted to be detachably coupled to an artificial hand, a rotary driving member within and extending axially of the wrist fitting for imparting rotary movement to the hand when coupled to the wrist fitting, a pair of pulleys within said arm, said pulleys being spring biased to a home position and being rotatable in opposite directions away from said home position by traction on a flexion cord, a pair of gear wheels, one associated with each of said pulleys, a toothed wheel meshing with both of said gear wheels and arranged to impart rotary movement to said driving member, means for alternatively coupling the gear wheels to the pulleys so that but one gear wheel at a time can be coupled to its pulley and a pawl and ratchet gear which is rendered operative, as the pulleys near the home position, to reverse the couplings between the pulleys and the gear wheels.

4. An artificial arm, for use in cases of amputation below the elbow, and comprising a bucket to fit the stump, a wrist fitting attached to the bucket and adapted to be detachably coupled to an artificial hand, a rotary driving member within and extending axially of the wrist fitting for imparting rotary movement to the hand when coupled to the wrist fitting, a pair of pulleys within said arm, said pulleys being spring biased to a home position and being rotatable in opposite directions away from said home position by traction on a flexion cord, a pair of gear wheels, one associated with each of said pulleys, a toothed wheel meshing with both of said gear wheels and arranged to impart rotary movement to said driving member, a coupling pawl on each pulley, a ratchet associated with each gear wheel, control members for controlling the engagement of the coupling pawls with the ratchets, a toothed wheel, the teeth and inter-tooth spaces of which cooperate with the control members so as to permit but one of them to move into position to allow its coupling pawl to engage its ratchet, and means operative on return of said pulleys to home position to feed said toothed wheel forward into position to allow the other coupling pawl to engage its ratchet.

5. An artificial arm as claimed in claim 4, comprising a carriage mounted for sliding movement within the arm, pins on the pulleys for engaging said carriage, when said pulleys move towards their home position, to move said carriage into a normal position, a spring for moving said sliding carriage into a displaced position when freed by the pins, a reversing pawl on said sliding carriage, and a reversing ratchet associated with said toothed wheel, said reversing pawl cooperating with said reversing ratchet to feed said toothed wheel forward on return of the carriage to normal position by said pins.

6. An artificial arm as claimed in claim 5, comprising a cam member which is operative to disengage both coupling pawls from their associated ratchets in the home position of said pulleys, said cam member freeing said coupling pawls for movement into engagement with said associated ratchets only after the pulleys have moved away from a home position a distance sufficient to enable said pulleys, by return to home position,

70 to actuate said reversing pawl.

7. An artificial arm as claimed in claim 4, comprising a manually operable lever projecting from the arm and operable to render said feeding means ineffective to feed said toothed wheel forward.

7
 8. An artificial arm as claimed in claim 4, comprising a carriage mounted for sliding movement within the arm, pins on the pulleys for engaging said carriage, when said pulleys move towards their home position, to move said carriage into a normal position, a spring for moving said sliding carriage into a displaced position when freed by the pins, a reversing pawl on said sliding carriage, a reversing ratchet associated with said toothed wheel, said reversing pawl cooperating with said reversing ratchet to feed said toothed wheel forward on return of the carriage to normal position by said pins, a manually operable lever projecting from the arm,

5 and a catch movable by said lever into position to latch the carriage against movement from its displaced to its home position.

JOYCE OTTERMAN.
